UNITED STATES PATENT OFFICE

2,554,093

APPARATUS FOR MANUFACTURING TUBES
AND THE LIKE FROM FLAT METAL STRIPS
OR BANDS

Lucien Desilly, La Louviere, Belgium

Application July 23, 1948, Serial No. 40,273
In Belgium August 6, 1947

6 Claims. (Cl. 153—54)

1

The present invention relates to an apparatus for manufacturing tubes and the like by bringing together the edges of flat metal strips or bands.

In accordance with my invention, the strip or band is subjected to a gradual and continuous deformation under such conditions that the finished articles have exactly the desired cross-section and size and permanently keep their shape. The flat strips or bands are engaged between two grooved surfaces moving in unison, said surfaces being separated by a wedge-shaped space of curved outline, so that the strip or band engaged therebetween is progressively and continuously bent until its two edges are brought together and the desired shape is obtained.

It is the object of this invention to provide a simple and efficient apparatus for manufacturing tubes as aforesaid. Such apparatus comprises two circular rotatable members, one being an internally grooved ring and the other an externally grooved disc mounted eccentrically within said ring, with its outer edge adjacent the inner edge of the ring. The two members are rotated in the same direction and their grooves co-operate to bend the strip longitudinally and to gradually shape it to tubular form. The disc may be adjusted in position to meet requirements. Suitable means are provided for guiding the strip into the space comprised between the two grooves and for directing the tube out of the apparatus.

In order that the invention shall be more readily understood reference will be had to the accompanying drawings which illustrate by way of example two constructional forms of my improved apparatus.

Fig. 1 illustrates diagrammatically, in cross-section on line I—I of Fig. 2, the essential parts of a horizontal apparatus.

Fig. 2 is a plan view of same.

Figs. 3, 4 and 5 are cross-sectional views, similar to Fig. 1, illustrating modified arrangements of the parts.

Figs. 6, 7, 8 and 9 respectively show successive phases in the manufacture of a tube in the apparatus shown in Figs. 1 and 2.

Fig. 10 is a view in elevation illustrating a vertically arranged apparatus.

Figs. 11 and 12 are cross-sectional views on line XI—XI and XII—XII respectively of Fig. 10.

Figs. 1 and 2 illustrate the disc 10 and ring 11 which are the main essential parts of the apparatus. The disc 10 is substantially smaller than and is arranged eccentrically within the ring 11. Both disc and ring are rotated in the same direction, their respective centers being shown at 12

2

and 13 in Fig. 2. It will be understood that by varying the distance between said centers the shape of the cross-section of the finished article can be varied.

5 In the outer periphery of the disc 10 and the inner periphery of the ring 11 are provided semi-circular grooves which define together a space 14 between the two rotating members, which space is of circular cross-section where the said members are adjacent, as shown on the right hand side of Fig. 1. Where the disc and ring are spaced apart, I may provide leading in rolls 15, 15a (Fig. 1) or a fixed guide 16 (Fig. 3) or a rotary guide piece which may be a side flange 10a on disc 10 (Fig. 4) or a side flange 11a on ring 11 (Fig. 5).

In operation disc 10 and ring 11 are rotated in the same direction, as shown for example in Fig. 2 by the arrow x. The flat strip 17 to be shaped 20 is introduced into the space 14 at y, where the open gap between the parts 10 and 11 is wider than the width of the strip. It is caught between the rolls 15, 15a whereby it is guided into the space 14 which has the general shape of a curved wedge tapering from y to z. While it nears the point of maximum construction z, the strip 17 is gradually shaped by the grooves defining the space 14 as illustrated in Figs. 6 to 8. At z shaping is completed and the strip is bent edge to edge into a tube 17a (Fig. 9). Additional pairs of rolls such as 15, 15a may be provided between y and z, or other guide pieces such as the plate 16 or the flanges 10a or 11a may be provided.

35 Beyond z, the space between disc 10 and ring 11 again increases in cross-section, so that the finished tube can be diverted side wise and withdrawn from the apparatus.

In the form of apparatus illustrated in Figs. 40 10 to 12, the disc 10 and ring 11 are arranged vertically in eccentric relation to each other and they are provided with toothed rings 18, 18' respectively, in mutual engagement, so that they are adapted to rotate in unison in the same direction. The disc 10 is driven by its shaft 19 which is journalled in bearings 20 and is rotated from a motor 21 through reducing gears 22, 23, whereas the ring 11 is freely supported on rollers 24 journalled in the casing 25 which is made of 45 two parts to provide easy access to the inside of the apparatus.

The strip or band to be shaped (not shown) is fed to the apparatus by means of guiding rolls 26, 27, 28.

50 The first pair of rolls 26 have peripheral grooves

for engaging the edges of the strip which is fed in a vertical plane. The distance between the rolls 26 is regulable by means of a screw 36 which engages threaded holes in pins 31 carrying the rolls 26, said pins being slidable towards and away from each other in a frame 29 secured to the casing 25. The pins 31 are each made of two parts connected by a vertical pivot 30 so that the angular position of the rolls 26 and consequently of the strip can be varied as required.

Being guided by the rolls 26 the strip enters the casing 25 through an opening 32 and is then caught by the second pair of rolls 27 which is almost in line with the shaping gap 14. The rolls 27 are preferably slightly curved as shown in order to initiate the shaping operation.

Just before the point where the strip is caught between the disc 10 and ring 11 is a further guiding roll 28 which leads the slightly curved strip into the gap 14 where the shaping operation is completed in the manner shown in Figs. 6 to 9. A window 33 is provided in the wall of the casing 25 to permit of watching and if necessary correcting the positioning of the strip in the shaping space 14.

The finished tube is led away through the side of the casing opposite the inlet side, the outlet side of the casing being provided with a funnel-shaped guide 34 merging into an outlet pipe 35 of sufficient length to cause the outgoing tube to straighten up.

It will be understood that the shape of and distance between the grooves in the disc and ring may be varied according to the shape of the articles to be produced and that details of construction of the apparatus may be varied without departing from the invention as defined in the appended claims.

I claim:

1. An apparatus for making substantially continuous tubes by longitudinally bending a flat metal strip, comprising a ring having a shaping surface on its inner periphery, a disc having a shaping surface on its outer periphery, said respective shaping surfaces being complementarily concave with respect to one another, said disc being mounted eccentrically within said ring and

adjacent its inner periphery, means for rotating said disc and ring in unison in the same direction, means for guiding said strip into the space between said disc and said ring for progressive edge-on deformation thereby, and means for guiding the substantially continuous, tubular shaped strip out of said space.

2. An apparatus as claimed in claim 1, having means for closing at least one side of the space 10 formed between the shaping surface on said ring and the shaping surface on said disc.

3. An apparatus as claimed in claim 1, wherein the shaping surfaces on said ring and said disc are of semi-circular outline.

4. An apparatus as claimed in claim 1, wherein the means for guiding said strip into the space between said disc and said ring comprise a pair of grooved rollers arranged at an angle outside said ring and at least a pair of rollers arranged within in said ring.

5. An apparatus as claimed in claim 1, wherein the means for guiding said strip into the space between said disc and said ring comprise a pair of coacting rollers having curved peripheral surfaces for imparting an initial curvature to the strip to be shaped.

6. An apparatus as claimed in claim 1, wherein the means for guiding the shaped strip out of the space between said disc and said ring comprise a funnel-shaped outlet followed by a straight outlet tube.

LUCIEN DESILLY.
